CHAIR CONSTRUCTION

Richard L. Panicci, Northampton, Mass., assignor to
Hampden Specialty Products, Inc., Easthampton,
Mass., a corporation

Application July 7, 1958, Serial No. 746,745

2 Claims. (Cl. 155—191)

This invention relates to new and useful improvements in a chair construction, and is directed more particularly to a chair of the type generally known as a straight back chair.

The principal object of the invention is directed to the provision of a chair having rigid frame components for the seat and back supporting members which are of a somewhat yieldable material such as leather, plastic, fabric, or the like as customarily employed in chair manufacture.

According to novel features of the invention, the yieldable back supporting member of the chair is constructed and arranged to space the upper portion of the back of the occupant of the chair away from, or forwardly of, the upper rigid portion of the chair frame, so as to obviate contact of the occupant's upper back portion with the more rigid chair frame.

In chairs where yieldable material has been employed for the back rest, the material tends to sag or belly rearwardly so that the upper back portion of the occupant of the chair bears on the rigid frame of the chair, and he experiences considerable discomfort which of course is objectionable.

In a general way, the yieldable back rest of the chair of this invention is formed so that the marginal portion thereof, more particularly the upper rear portion of the back rest, inclines rearwardly and upwardly from a curving line to the upper rigid part of the chair frame. An occupant's back is supported along this line against rearward movement and thereby that portion of the back upwardly of said line is held away from or spaced forwardly of the chair frame for the utmost comfort of the occupant of the chair.

Various changes and modifications may be made in a chair, without departing from the spirit and scope of the invention, which, for purposes of disclosure, is shown in the presently preferred form thereof by the accompanying drawing wherein:

Fig. 1 is a side elevational view of a chair embodying the novel features of the invention;

Fig. 2 is a front elevational view of the chair shown in Fig. 1;

Fig. 3 is a sectional view on the line 3—3 of Fig. 2, through the rear portion of the chair shown in Fig. 2;

Figs. 4, 5, and 6, are small scale plan views of the seat support, front leg member, and back leg member respectively of the chair shown in Figs. 1 and 2; and

Fig. 7 is a sectional elevational view through the upper rear member of the chair showing the seaming in a different relation than in Fig. 3.

Referring now to the drawings more in detail, the novel features of the invention will be fully described.

The parts, shown in Figs. 4, 5, and 6 and to be described, will preferably be formed from tubing, such as is commonly used in chair construction.

A seat support 2, shown in Fig. 4, is circular or ring-like in form, and a seat 4, supported thereby, and made from suitable plastic, leather, composition, fabric or what-

2

ever may be desired, is secured thereto by a marginal tubular bead 6, having a draw string or cord 8 therein. The cord draws the marginal portions of the seat inwardly, in the well known manner.

5 A front leg member 10, shown in Fig. 5, has a horizontal semi-circular rear portion 12 underlying the rear portion of the seat support 2, and a pair of transversely spaced legs 14 which incline downwardly and forwardly, as shown in Figs. 1 and 2.

10 A back and rear leg member 16, shown in Fig. 6, is in the form of a U having an uppermost rear transverse portion 18. The side portions of the member provide arm portions 20 which decline downwardly and forwardly from the transverse upper portion 18, and transversely spaced leg portions 22 which depend rearwardly and downwardly.

15 The leg portions 22 are secured to the seat support 2, and to the member 12 by screws, bolts, or the like indicated by 24, so as to provide a strong rigid chair frame structure.

20 The back rest of the chair includes a main body portion 26, and a marginal portion 28, which are formed from a somewhat yieldable or pliable material, which may consist of plastic, fabric or whatever may be desired.

25 The main body portion 26 has a lower edge portion 26' which underlies the semi-circular portion 12 of the front leg member 10, and is secured thereto by the well known snap fastener devices 30, or by other suitable means.

30 The upper edges 32 and opposite side edges 34 of the marginal portion 28 of the back rest are secured to the rear and side portions 18 and 20 of member 16, by snap fasteners 36.

35 The body portion 26 and the marginal portion 28 of the back rest have edge portions that are joined or seamed by stitching, as indicated by 40. The edges are so shaped and the seaming is such that the seam is generally of U shape, and has side portions 40' extending rearwardly from the forward ends of the arms 20 to a curving rear portion 40''.

40 The main body 26 of the back rest is U shape in horizontal cross section, and the rearward portion thereof inclines upwardly and rearwardly to some extent, as indicated in Fig. 3.

45 The rear curving portion 40'' of seaming is disposed below the horizontal plane of the upper rear portion 18 of frame member 16, and forwardly thereof so that the marginal portion 28 inclines upwardly and rearwardly relative to the main body portion 26, and to the upper rear portion 18 of the frame, to which it is secured.

50 The seaming is formed in such a manner as to act as a U-shaped brace, and will be of a character as to be relatively non-yielding rearwardly whereby the upper portion of the back of the occupant of the chair is spaced forwardly of the upper rear portion 18 of the chair frame.

55 The seaming or jointure of the components 26 and 28 of the back rest may be accomplished in various ways. The edges of the components may be secured together by stitching or by any desired means, and if desired, reinforcement may be incorporated therein to obviate appreciable rearward yielding of the jointure whereby the back of the occupant of the chair is spaced forwardly from and out of contact with the chair frame.

60 The components of the back rest are shown as being attached to the chair frame to facilitate removal therefrom, but they may be secured to the frame by any desired means.

65 The seaming at the back edge of the chair may be related as desired to the upper portion 18 of the chair frame. As shown in Fig. 7, the seaming is more forwardly and at a higher point than in Fig. 3. Obviously the

seaming may be arranged to be located where desired, and will depend upon the arrangement of the chair frame, the materials from which components 26 and 28 are made, and other factors.

Various changes and modification may be made within the spirit and scope of the invention, and it is desired to be limited, if at all, by the appended claims rather than by the foregoing description of the preferred form of the invention.

I claim:

1. In chair construction including a leg supported horizontal seat having opposite sides and a rear end with opposite arms spaced above the opposite sides of the seat inclining rearwardly and upwardly to an upper transverse rear back member disposed rearwardly outwardly of the vertical plane of the rear end of the seat, the improvement comprising, a body supporting structure of relatively yieldable material including a main body member and a marginal member, said main body member having a lower marginal portion secured to opposite sides and rear end of the seat and extending upwardly therefrom to an upper marginal portion, said marginal member having an outer marginal portion secured along said back member and arms and extending inwardly therefrom to an inner marginal portion, said upper and inner marginal portions of said main body and marginal members being joined by seaming in the shape of a U having a concave rear portion and opposite side portions extending therefrom to forward portions of said arms, said concave rear portion of said seaming being disposed forwardly and inwardly of said back member and upwardly relative to the horizontal plane of said seat whereby the upper back portion of an occupant of the chair is supported by the concave portion of the seaming forwardly of and away from said back member. 35

2. Chair construction comprising in combination, a frame including a horizontal seat having opposite side and a rear end portion and transversely spaced front and rear legs extending downwardly from said seat and oppo-

site side arms spaced above opposite sides of said seat inclining rearwardly and upwardly to opposite ends of an upper transverse rear back portion spaced above and horizontally outwardly from the rear end portion of said seat, a two-part body support formed from yieldable material having a main body member and a marginal member, said body member having lower marginal edge portions secured to the opposite sides and rear end of the seat and extending upwardly therefrom, said marginal member having outer marginal edge portions secured to the upper transverse rear back portion and side arms of the frame, inner edge portions of said marginal member and upper marginal edge portions of said body member being joined together by seaming arranged in the form of a U having a concave back supporting portion and opposite side portions, said back supporting portion being disposed inwardly of the upper back portion of the frame and upwardly from the plane of said seat and said side portions of said seaming extending from said concave supporting portion to forward portions of said side arms whereby the upper back portion of an occupant of the chair is supported by the rear concave portion of the seaming forwardly of and away from the upper back portion of the frame.
